UNITED STATES PATENT OFFICE

2,458,999

PRIMER AND IDLER

Will R. S. Mills, Crystal, Okla.

Application November 9, 1945, Serial No. 627,753

1 Claim. (Cl. 158—46.5)

1

This invention relates to a primer and idler for gasoline engines, and the like, and has for one of its objects the production of a simple and efficient means for connection with a downdraft carburetor to provide a reserve supply of fuel which may be conveniently fed to the carburetor in the event that the engine should fail to start.

A further object of this invention is the production of a simple and efficient means for filling a reserve tank with fuel while the engine is operating so that this reserve supply of fuel may be used subsequently to start the engine.

Other objects and advantages of the present invention will appear throughout the following specification and claims.

In the drawing:

Figure 1 is a side elevational view of the primer and idler;

Figure 2 is an enlarged longitudinal sectional view, certain parts being shown in elevation;

Figure 3 is a top plan view of the vented cap of the reserve tank.

By referring to the drawing, it will be seen that 10 designates a hollow coupling one end of which is adapted to be connected to the fuel pump of a gasoline engine and the other end to a carburetor, as indicated in Figure 1. A joint 11 is also connected to the hollow coupling 10 by means of a connecting pipe 12, which pipe 12 extends vertically relative to the coupling 10. The joint 11 is provided with a longitudinal bore 13 extending from end to end and having a valve seat 14 intermediate the ends thereof for receiving the needle valve 15 to control the flow of gasoline or other fuel through the seat 14 when desired, by the adjustment of the valve 15. The bore 13 communicates with the hollow pipe 12 which pipe 12 forms a communication between the bore 13 and the hollow coupling 10, as shown in Figure 2. The bore 13 also communicates with the hollow pipe 16 which is connected to the end of the joint 11 opposite the needle valve 15.

A hollow metal or other bowl 17 is supported above the joint 11 by a hollow stand-pipe 18 forming a communication with the bore 13 and valve seat 14 with the bowl 17. The bowl 17 is provided with an upstanding threaded neck 19, upon which is threaded a vent cap 20 having a vent aperture 21. A gasket 22 fits between the cap 20 and the upper end of the neck 19 surrounding the area of the vent 21. The vent 21 may therefore be opened or closed by adjusting the cap upon the neck 19 relative to the gasket 22, such for instance, by turning the cap 20 upon the screw threads of the threaded neck 19.

2

The outer end of the pipe 16 is connected to a vertical joint or casing 23 having a bore or channel 24 which communicates with the bore 25 in the pipe 16. A vertically adjustable needle valve 26 controls the passage of fuel through the bore 24 by its movement toward or away from the valve seat 27, which seat is located in the bore 24. The lower end of the bore 24 communicates with the intake manifold of the engine and also communicates with the windshield wiper through the hollow nipple 28.

The present device is adapted to be connected to the fuel line or fuel pump and to a downdraft carburetor of a gasoline engine. As the gasoline engine is started, the bowl 17 fills quickly with gasoline, the valve 15 being open and the vent cap 20 also being loosened to open the vent 21. When the bowl 17 is full of fuel, the vent cap 20 is tightened or secured to close the vent 21 and the bowl will retain the fuel at all times if the fuel line is air-tight. If the fuel line is not tight the valve 15 is adjusted to close on the seat 14 to prevent fuel from leaking from the bottom of the bowl 17. This may be done whether the engine is in operation or not to insure the retention of a full bowl of fuel.

Should the engine fail to start, for lack of obtaining sufficient fuel through the fuel line and carburetor, the operator may simply open the valve 15, if it is closed, and unscrew the vent cap 20 to provide a proper vent for the bowl 17. The supply of filtered fuel which has been stored in the bowl 17 from the fuel pump, about one-half pint, will flow by gravity to the carburetor by way of the pipe 18, bore 13, pipe 12, and coupling 10. A suitable communication is provided between the intake manifold and the windshield wiper through the coupling or casing 23 and pipe 16 from the joint 11.

If the priming pump of the engine is not operating, the valve 26 may be opened to prime the intake manifold and may be kept open to permit the engine to idle while cold and until the engine warms up, when the valve may be closed to permit normal operation.

From the foregoing description it will be seen that a simple and efficient means has been provided for priming and facilitating the starting of a gasoline engine, should the engine fail to start due to the fact that the engine is cold or because of the lack of fuel being fed through the carburetor and intake manifold. It should be understood that the present device will prime the fuel-line and the carburetor, it being necessary to open the vent cap 20 and valve 15. The priming is

done by filtered gasoline from the bowl 17. Furthermore, should the engine fail to start in cold weather, the valve 26 provides means for priming the manifold and keeping the engine idling until it functions normally, thereby avoiding costly damage to the engine.

It should be understood that certain detail changes may be made in the present structure without departing from the spirit of the invention, so long as these changes fall within the scope of the appended claim.

Having described the invention, what is claimed is:

A device of the class described comprising a reservoir adapted to contain liquid fuel, a hollow carburetor and fuel pump coupling, a joint coupling forming a communication between the reservoir and the first mentioned coupling, an intake manifold connection, a pipe forming a communication between the intake manifold connection and the joint coupling, a valve for closing the intake manifold connection, a valve for closing the communication between reservoir and the joint coupling, and a normally sealed rotatable vent cap carried by the reservoir and having a vent opening which is adapted to be opened when

the cap is rotated in one direction and closed when the cap is rotated in an opposite direction to control the flow of liquid fuel from the reservoir and to hold the fuel within the reservoir when desired.
